UNITED STATES PATENT OFFICE.

FRANCIS S. ADAMS AND WILLIAM H. RICKARD, OF PUEBLO, COLORADO.

SLIDING DOOR.

1,111,634.

Specification of Letters Patent. Patented Sept. 22, 1914.

Application filed September 13, 1913. Serial No. 789,612.

To all whom it may concern:

Be it known that we, FRANCIS S. ADAMS and WILLIAM H. RICKARD, citizens of the United States, and residents of Pueblo, 5 county of Pueblo, and State of Colorado, have made certain new and useful Improvements in Sliding Doors, of which the following is a specification.

Our invention is an improvement in sliding doors, for automobiles and like vehicles, 10 wherein the body of the vehicle is provided with a recess or chamber adjacent to each door opening, for receiving the door, and wherein the door is mounted to slide into and 15 out of the chamber, and wherein mechanism is provided operable from the seat, for opening and closing the door, and wherein normally active mechanism is provided for locking the door in closed position, the said 20 mechanism being arranged in such manner that it may be released from the seat.

In the drawings: Figure 1 is a side view of a portion of the body of an automobile provided with the improved door, and Figs. 25 2 and 3 are enlarged sections on the lines 2—2, and 3—3, respectively, of Fig. 1, looking in the direction of the arrows.

The present embodiment of the invention is shown in connection with the body 1, of 30 an automobile, and the body is provided with a recess in one or both of its sides adjacent to the door opening, the said recess 2 being of such size that it will receive practically the entire door. The recess is in- 35 closed at the top by the upholstery of the seat 3, as shown in Figs. 1 and 2, and at the outer side of the said recess or chamber, other smaller recesses 4 and 5 are provided, the recess 4 being near the upper edge of 40 the side of the body, while the recess 5 is near the bottom of the chamber. The door is also chambered, and the said door may be of any suitable material, having the outer surface thereof to correspond with the finish of the car. The door consists of a sub- 45 substantially rectangular frame 6 and inner and outer side plates 7 and 8 respectively, and the outer face of the door is provided with a facing frame 9, thus forming a panel of the 50 outer plate 8.

Below the door opening is a passageway 10 in the body of the car, extending longitudinally of both the door opening and the chamber 2, and a track rail 11 is secured to 55 the body in the said passage, and at the bottom thereof. The track rail extends from

in front of the door opening to the rear wall of the chamber 2, and the said track rail is approximately triangular or T-shaped, as shown in Figs. 2 and 3.

The lower transverse bar of the door frame 6 is recessed on each face, at the bottom of the door, to form recesses or passages 12 at each face of the door, the said passages being between the plates 7 and 8 and 60 a rib 13 formed by recessing the said transverse bar from each side. A plate 14 is arranged above the passageway 10, the body of the car being rabbeted at each side of the passage to receive the edges of the said plate, and the plate is provided with a longitudinally extending slot 15.

The rib 13 before mentioned, extends through the slot, and at its lower end the said rib is enlarged laterally, as shown in 75 Fig. 2, and the under face of the rib is longitudinally grooved, as shown at 16. The lateral enlargement of the rib below the plate 14 provides a shoulder 17 at each side of the rib, between the enlarged portion and 80 the main portion, and the said shoulders engage below the plate 14. Grooved wheels 18 are journaled in the groove 16, one of the wheels being preferably arranged at each side edge of the door, and the said wheels 85 run upon the track rail 11, before mentioned. Other wheels 19 are journaled on each side of the rib 13, above the plate 14, the said wheels being mounted on a journal pin 20, which extends transversely of the rib, and 90 engages at its ends the side plates 7 and 8. The recesses 12 before mentioned, are at the side edges of the door only, as shown in Fig. 2, the said recesses being of a depth and width just sufficient to receive the wheels 19. 95 The groove 16, however, extends the full width of the door.

The wheels 19 run upon the upper surface of the plate 14, and the door is thus supported by six wheels, four wheels resting on 100 the plate 14 on each side of the slot 15, and the other wheels resting upon the track rail 11. At the rear side edge the door is recessed near its top and bottom, as indicated at 21, and an eye 22 is connected to the door 105 in each of the recesses. One end of a flexible member 23, as for instance a rope or cord, is connected to each of the eyes, and at its other end each of the flexible members winds upon a reel 24, the said reels being journaled 110 in the recesses 4 and 5 before mentioned. The said reels are journaled on shafts 25,

and the recesses 4 are of a width to receive the reels, the shafts 25 extending beyond the recesses on each side, and being journaled in the body of the vehicle, as shown. The reels 5 24 are spring operated, to wind up the flexible members 23, and when the door is released from the locking means, to be later described, the springs are of sufficient strength to open the door. The recesses 21 10 of the door register with the recesses 4 and 5 of the body, and the said recesses 21 receive that portion of the reels 24 which project outside of the recesses 4, when the door is opened.

15 Near its front edge, the door is provided with a grip or handle 26 for convenience in closing the same, and locking mechanism is arranged at the rear edge of the door. The said mechanism comprises a bolt 27, mounted 20 for vertical sliding movement in a bracket 28, secured to the body between the inner and outer surface thereof, and the bolt is normally pressed into engagement with an opening in the top of the door, by means of 25 a coil spring 29.

A lever 30 is pivoted between the inner and outer surface of the upholstery of the seat, intermediate the ends of the lever, as indicated at 31, and one end of the lever is 30 pivoted to the upper end of the bolt 27. A push button 32 is mounted for vertical sliding movement in the upholstery of the seat, and the lower end of the push button is connected with the end of the lever remote from 35 the bolt. The upper end of the push button extends slightly above the upholstery, and the arrangement is such that when the button is depressed the bolt will be lifted, to release the door, and to permit the springs 40 in the reels 24 to open the door. The door is guided by the engagement of the plate 7 with the inner side wall of the chamber 2, and by the engagement of the facing frame 9 with the outer side of the chamber.

45 Within the passage 10, a series of guides is arranged on each side wall thereof, each guide consisting of a body 33 having its ends offset laterally, as shown at 34 and secured to the side walls of the passage 10. The 50 bodies of the guides engage the opposite faces of the enlarged portion of the rib 13, to prevent lateral movement of the bottom of the door. It will be noticed from an inspection of Fig. 3, that the said ribs are 55 so arranged that the door is always in engagement with a pair of oppositely arranged guides.

In operation, the bolt 27 normally holds the door closed, against the traction of the 60 flexible members 23. When it is desired to open the door, the button 32 is depressed, thus lifting the bolt 27 and releasing the door. Reels 24 immediately wind up the flexible members 23 and open the doors, the 65 door rolling on the wheels 18 and 19.

When it is desired to close the door, the grip 26 is made use of, the grip being grasped and pushed toward the front of the car. As soon as the bolt 27 comes in register with the opening of the door, it will drop 70 into place and will hold the door closed. The springs of the reels 24 will hold the door open.

It will be noticed from an inspection of Fig. 1, that the door is provided with an 75 extension or projection 35 at its front edge, and at its bottom, and the said projection is adapted to enter a notch or recess 36 in the frame of the automobile, to prevent the door from tipping or from rattling. When 80 the door is closed the projection engages the recess in the manner specified, to hold the door in place.

We claim:

1. The combination with a vehicle having 85 a door opening, and a chamber at one side of the door opening, of a door mounted to slide into and out of the chamber for closing the opening, said vehicle having a passage-way below the door opening and extending 90 into the chamber, a track rail in the passage, a plate above the passage, said plate having a longitudinal slot, pairs of wheels journaled on the door, said pairs being near the opposite side edges of the door, and the members of each pair being on opposite faces of the door, said wheels engaging a plate, said door having an extension passing through the slot and into the passage, wheels journaled on the extension and engaging the 95 track rail, normally active means within the chamber for opening the door, a spring latch for holding the door closed, a push button adjacent to the seat, and a connection between the said button and the latch for 100 releasing the latch when the button is depressed.

2. The combination with a vehicle having a door opening, and a chamber at one side of the door opening, of a door mounted to 110 slide into and out of the chamber for closing the opening, said vehicle having a passage-way below the door opening and extending into the chamber, a track rail in the passage, a plate above the passage, said plate having 115 a longitudinal slot, pairs of wheels journaled on the door, said pairs being near the opposite side edges of the door, and the members of each pair being on opposite faces of the door, said wheels engaging a plate, said door having an extension passing through the slot and into the passage, wheels journaled on the extension and engaging the track rail, normally active means within the chamber 120 for opening the door, and releasable means 125 for holding the door closed.

3. The combination with a vehicle having a door opening, and a chamber at one side of the door opening, of a door mounted to slide into and out of the chamber for closing 130

the opening, said vehicle having a passage-way below the door opening and extending into the chamber, a track rail in the passage, a plate above the passage, said plate having 5 a longitudinal slot, pairs of wheels journaled on the door, the members of the pairs being on opposite sides of the slot, said door having an extension passing through the slot, wheels journaled on the extension and en- 10 gaging the track rail, normally active means for opening the door, and releasable means for holding the door closed.

4. The combination with a vehicle having a door opening, and a chamber at one side 15 of the door opening, of a door mounted to slide into and out of the chamber for closing

the opening, said vehicle having a passage-way below the door opening and extending into the chamber, a track rail in the passage, a plate above the passage, said plate having 20 a longitudinal slot, pairs of wheels journaled on the door, the members of the pairs being on opposite sides of the slot, the door having an extension passing through the slot, and wheels journaled on the extension 25 and engaging the track rail.
